DESIGN FOR A COMBINED BILLFOLD AND
COIN PURSE

John P. Reis, West Bend, Wis., assignor to Amity
Leather Products Co., West Bend, Wis., a cor-
poration of Wisconsin

Application February 20, 1947, Serial No. 137,038

Term of patent 7 years

(Cl. D87—3)

To all whom it may concern:

Be it known that I, John P. Reis, a citizen of the United States, residing at West Bend, in the county of Washington and State of Wisconsin, have invented a new, original, and ornamental Design for a Combined Billfold and Coin Purse, of which the following is a specification, reference being had to the accompanying drawing, forming a part thereof, and in which:

Figure 1 is a top edge view; Figure 2 a front side view; Figure 3 an end view; Figure 4 an interior view; Figure 5 an end view, showing the interior fittings; and Figure 6 a bottom edge view, of a combined billfold and coin purse embodying my new design. The stippling and shade lines shown in the drawing are used conventionally to show contrast between materials in different portions of the purse.

The characteristic features of the present design reside in the inner contours of the purse, as shown in Fig. 4, and particularly the loose pocket flap which extends above the fold line, as shown particularly in Figs. 4 and 5.

I claim:

The ornamental design for a combined billfold

and coin purse, substantially as shown and de-
scribed.

JOHN P. REIS.
